UNITED STATES PATENT OFFICE.

WILLIAM A. DROWN, OF ABINGTON, PENNSYLVANIA.

DESIGN FOR A PARASOL.

SPECIFICATION forming part of Design No. 12,937, dated May 23, 1882.

Application filed April 10, 1882. Term of patent 7 years.

To all whom it may concern:

Be it known that I, WILLIAM A. DROWN, a citizen of the United States, and a resident of Abington, Montgomery county, Pennsylvania, have invented a new and original Design for a Parasol, of which the following is a specification.

My design is fully shown in the accompanying photographic illustration.

10 The design comprises the ruffled border *a*, which is applied to and projects beyond the edge of the parasol-cover *b*, as shown, the inner edge of the ruffle being Shirred—that is to say, provided with a number of parallel rows 15 of fine puffs, *d*. The ruffle is in the present

instance edged with lace; but this is not essential.

Irrespective of the colors employed, I claim—

The design for a parasol, said design comprising the cover *b*, with the shirred ruffle *a d*, 20 forming a border thereon, as shown and described.

In testimony whereof I have signed my name to this specification in the presence of two subscribing witnesses.

WM. A. DROWN.
